COASTER

Layard L. Campbell, Bronxville, N. Y.

Application April 18, 1938, Serial No. 202,808

3 Claims. (Cl. 65—53)

This invention relates to improvements in coasters.

Objects

Among the principal objects which the present invention has in view are: to provide a coaster having means whereby a goblet or the like will be removably held secure therein; to provide means within the coaster for absorbing moisture released from the goblet or the like; to be enabled to readily remove the goblet or the like from the coaster; to prevent a goblet or the like from becoming disengaged from a coaster while in use; to provide a coaster having means to snugly retain a tumbler or the like therein; to be enabled to remove the tumbler or the like from the coaster when desired; to be enabled to replace the moisture absorbing means when desired; to secure simplicity of construction and operation; and to obtain other advantages and results from the following description.

Drawing

Figure 1 is a front elevation of my improved coaster showing a goblet or the like held in place 25 therein;

Figure 2 is a top plan of the coaster alone, showing the means whereby a goblet or the like is held therein;

Figure 3 and Figure 4 are sectional views shown 30 as taken on lines 3—3 and 4—4 respectively of Figure 2;

Figure 5 is a front elevation of another form of coaster with a tumbler or the like held therein;

Figure 6 is a vertical sectional view taken on line 6—6 of Figure 5 with the tumbler or the like in elevation; and

Figure 7 is a fragmentary sectional view of a portion of the coaster and showing in detail the means for engaging the tumbler or the like and 40 holding the same snugly therein.

Description

In the specific embodiment of the invention illustrated in said drawing, and alluding initially 45 to Figs. 1 to 4 inclusive, the reference numeral 10 indicates, in general, a coaster of my invention constructed more particularly for association with a conventional goblet 11 having a stem 12 and foot 13. The coaster is shown to be circular 50 in the drawing, to agree with the conventional circular shape of said foot 13 of the goblet, but it is to be understood that other shapes may be employed under the broad concept of the invention. The said coaster preferably provides a solid bot- 55

to provide an upstanding side wall 15 which in turn curls inward as at 16 at its upper edge to provide a narrow inwardly directed rim. The inside diameter of the coaster at its rim 16 is greater than the maximum diameter of the foot 13 of the goblet 11, so that the said foot may be readily inserted into the coaster and may rest upon the said bottom wall 14 thereof. Likewise, the height of the upstanding side wall is greater than the height of the foot 13 so that the said foot will be entirely within the coaster when resting on said bottom wall.

It is a well known fact that goblets will sweat, and coasters have been heretofore employed to permit the condensation to pass into the coaster and not cause any damage to the table or other surfaces where the goblet is rested. However, the condensation accumulating in the coaster or upon the foot of the goblet when it is raised for drinking purposes is frequently sufficient that it will 20 drip from the goblet when the same is raised from the coaster for drinking or other purposes. This results, prior to the present invention, in the drops of water or of overflow from the goblet when such occurs, dripping onto the table or elsewhere.

According to the present invention, dripping is avoided by mounting the coaster upon the foot of the goblet so that, when the goblet is raised, the coaster is also raised and continues to retain and collect the condensation on the outside 25

of the goblet as well as any overflow from the goblet. In accomplishing this result, I preferably provide a spring retainer 17 as part of the coaster and of a character which will engage the

goblet and retain the coaster and goblet together. 30

The retainer shown in the figures now being described is preferably of wire construction, having a configuration very similar to a hairpin, or, more explicitly having a pair of legs 18, 18 substantially of a length equal to the diameter of the 35

coaster and integrally formed by an end or cross portion 19. The retainer is preferably of resilient metal and constructed to tend to normally spread the legs apart, as shown in full lines in 40

Fig. 2. The outer or free ends of the retainer 45 preferably curl upwardly as at 20 for obtaining appropriate contact with the said wall of the coaster and to underlie the said rim 16 when said legs 18, 18 are spread apart. The parts are so

proportioned that, when said legs are squeezed 50 together, as indicated in dotted line in Fig. 2, the said free ends 20, 20 no longer underlie the rim 16 and accordingly may be swung upward as

shown in Fig. 3. This enables the goblet to be tilted and slid out of the coaster with the stem 55

55

12 moving laterally in the general direction toward the free end of the said retainer. It is to be understood that the side wall 15 of the coaster preferably provides holes 21, 21 at one part thereof of preferably spaced apart and at suitable elevation. Bottom wall 14 for receiving legs 18, 18 therethrough, by virtue of which the cross-connecting or end portion 19 is at the outside of the coaster, thereby avoiding likelihood of the retainer becoming separated from the coaster. Inasmuch as legs 18, 18 tend to normally spread apart, movement of the retainer outwardly through holes 21, 21 requires exertion of a force to squeeze the legs toward each other. Likewise, 15 there is a tendency for the retainer to work inwardly as a result of this inherent urge of the legs to spread apart, and it is found in practice that the free ends of the legs will seat and remain seated under rim 16 against side wall 15 without 20 any probability of inadvertent displacement. The goblet and coaster, by virtue of the retainer overlying foot 13 and at opposite sides of stem 12 are thus held assembled and the coaster is raised and lowered with the corresponding raising and lowering 25 of the goblet. However, when desired to remove the goblet from the coaster, for washing or other purposes it is simply accomplished by squeezing the ends of legs 18, 18 toward each other and raising them as above described.

30 It is a further feature of the present invention to prevent any accumulation of liquid in the coaster from spilling therefrom when the goblet is tilted. In carrying out this feature, I preferably provide a cup or lining 22 of absorbent 35 material, such as blotting paper or the like, having appropriate shape to fit nicely within the coaster covering the upper side and bottom wall 14 and the inside of upstanding wall 15. This lining 22 will function to retain the moisture 40 where received and thus there will not be any free liquid flowing around within the coaster. The absorbent material likewise has the added function of forming a soft pad separating the material of the goblet foot from the material of 45 which the coaster is formed and thereby reducing likelihood of breakage or chipping of the goblet foot. The lining 22 is preferably pre-formed, although not necessarily so, and is shown with a cut out 23 at one part of its side wall for obtaining proper clearance for the retainer where said 50 retainer passes through the side wall of the coaster. The lining is readily replaceable, and it is preferable that a fresh lining be inserted after every use or washing of the goblet and coaster so that when the assembly is next used 55 the lining will be both dry and clean.

While the above description is particularly di-

rected to a construction for use in connection with coasters applied to goblets, features of the invention are applicable to other types of drinking and other vessels. Illustrative of this fact, I have shown a tumbler 24 in Figs. 5 and 6 5 mounted in a coaster 25 and having an absorbent lining 26 between the coaster and the tumbler. In this instance, the said lining preferably flares, as at 27 at its upper rim so as to very positively receive and absorb the moisture at the outside of 10 the tumbler. Suitable retaining means, such as the vertically disposed inwardly pressed leaf springs or fingers 28 are provided for securing the desired frictional contact between the coaster and tumbler. As shown, these spring fingers 28 are 15 integral at their upper ends with the side wall of the coaster and have their side and bottom edges free from the coaster wall so as to exert the desired spring tension. Benefits above described with respect to assembly and the parts 20 thereof, apply in connection with the assembly and parts of the disclosure of Figs. 5 to 7 likewise.

Obviously other detail changes and modifications may be made in the construction and use of my improved coaster, and I do not wish to be understood as limiting myself to the particular forms shown except as set forth in the following claims when construed in the light of the prior art.

I claim:

1. A coaster comprising a bottom and side wall, and a retainer projecting through said side wall and having spring arms extending across the coaster and in spreading apart adapted to engage said side wall and thereby mount both ends of 35 the retainer with respect to the coaster.

2. A coaster comprising a bottom and side wall, said side wall at its upper edge having an inwardly directed rim, and a retainer projecting through said side wall and having an inwardly 40 directed upper arm having a pair of yieldable legs extending across the coaster and in spreading apart adapted to engage said side wall beneath said rim and thereby mount both ends of the retainer with respect to the coaster.

3. A coaster comprising a bottom and side wall, said side wall at its upper edge having an inwardly directed rim, and a retainer projecting through said side wall and having an inwardly 45 directed upper arm having a pair of yieldable legs extending across the coaster and in spreading apart adapted to engage said side wall beneath said rim and thereby mount both ends of the retainer with respect to the coaster, and an absorbent lining within said coaster.

LAYARD L. CAMPBELL.
